UNITED STATES PATENT OFFICE.

HENRY A. DUC, JR., OF CHARLESTON, SOUTH CAROLINA.

MARINE ENGINE.

No. 833,591.

Specification of Letters Patent.

Patented Oct. 16, 1906.

Application filed December 21, 1905. Serial No. 292,878.

To all whom it may concern:

Be it known that I, HENRY A. DUC, JR., of Charleston, in the county of Charleston and State of South Carolina, have invented certain new and useful Improvements in Marine Engines; and I hereby declare that the following is a full, clear, and exact description thereof, reference being had to the accompanying drawings, which form part of this specification.

This invention is an improvement in elastic-fluid turbine-engines of the marine type and involves a novel construction of the turbine-engine and of the propeller operated thereby, which latter is utilized to maintain a partial vacuum around the shaft-journals, so that the necessity of tight stuffing-boxes around the shaft is obviated, with resultant lessening of friction upon the shaft, and the propeller may also be utilized to reduce the skin friction on the operative parts of the engine by partially exhausting the chambers in which the moving parts operate. The propeller may also be utilized to produce a circulation of water or other fluid medium around the shaft and bearings.

The invention embodies a novel construction of the reaction turbine-engine by which the propeller can be rapidly driven in either direction and reversed at will.

It also embodies a novel construction of propeller whereby the blades of the propeller are utilized as a means for creating a suction in the shaft-tunnel and in the idle or non-working chambers and passages surrounding the rotative parts of the engine and shaft.

The several features of the invention for which protection is desired are set forth in the claims, and I will now describe the invention in detail in connection with the particular embodiment thereof illustrated in the drawings, which will suffice to impart a clear understanding thereof; but it should be understood that the invention is not restricted to the particular form of apparatus disclosed in the drawings.

In the drawings, Figure 1 is a longitudinal section elevation of a reaction turbine-engine, the shaft tunnel or casing, and propeller-shaft and a side elevation of the propeller operated by said engine. Fig. 2 is an end elevation of Fig. 1. Fig. 3 is an enlarged sectional view of one of the propeller-blades. Fig. 4 is an enlarged detail section of part of

the propeller-hub and the adjacent parts of the propeller-shaft housing. Figs. 5 and 6 are detail views.

The engine illustrated in the drawings comprises an annular expansion-chamber A, which is formed within a suitable casing and has an annular opening a^3 around its inner periphery, within or close to which opening is fitted the periphery of the reaction-wheel W, which in this instance is a double wheel having two oppositely-arranged series of curved jet-passages $w w'$, which are formed on opposite sides of the wheel, but have no communication with each other, and their outlets into the chamber A are separated by the projecting periphery of the central disk D.

The jet-passages communicate with inlet-chambers at the axis of the wheel, which inlet-chambers communicate with axially-disposed jet-passages J and J', formed in annular castings J⁴ and J⁵, attached to the casing of the engine, which castings are provided with receiving-chambers c' c⁴ at opposite sides of the wheel, which respectively communicate with steam or elastic-fluid supply pipes T and T', which may be connected with any suitable source of elastic-fluid supply. The reaction-wheel W and its inner parts, so far as each face of the wheel is concerned, is constructed substantially like the wheel shown and described in my application for Letters Patent, filed November 23, 1905, Serial No. 288,750; but in this case the jet-passages on the opposite sides of the wheel W being inclined in opposite directions it is obvious that steam can be admitted only to one side of this wheel at a time, and when admitted to one side of the wheel it will rotate the wheel by reaction in the direction opposite to that in which it will be rotated when steam is admitted in the other side of the wheel.

Thus to drive the wheel and propeller, say to the right, steam might be admitted through the pipe T, or if it is desired to reverse the wheel and drive it to the left steam might be admitted to the pipe T'. Suitable valve mechanism may be employed, (not shown,) whereby one valve must be closed before the other can be opened.

The wheel is axially supported upon the main shaft C, which shaft is extended so as to form the propeller-shaft, the propeller P being mounted upon the outer end of the shaft. The shaft is supported at each side of the en-

gine in bearings F F' and adjacent to the propeller in bearing F². It may be provided with suitable collars f f' to prevent the longitudinal movement of the shaft in its bearings. Lubricant can be supplied to the bearings of the shaft from any suitable lubricant-supply through pipes l l' l². The oil admitted to bearings F would naturally be forced back by the pressure or leakage of steam to

- 10 the pocket h at the end of bearing F, to which access can be had through an opening closed by a removable screw-cap a, and any oil exuding from said bearing can be removed through pipe o to any suitable receiver.
- 15 (Not shown.) Similarly, the oil admitted to bearing F' may escape into a housing M, inclosing that portion of the shaft C between the bearing F' and F², and the oil exuded from bearing F' will be trapped in said housing by means of an annular flange r therein and can be removed through a drip-pipe o'.
- 20 The housing M' may be of any suitable construction and is to be air and steam tight. As shown, water can be circulated through this housing, if desired, by being admitted at the inlet g and removed at the outlet N through suitably-valved pipes, (not shown,) this means of circulating water being well known. Preferably, however, all the fluid
- 25 30 may be exhausted from said chamber and discharged through the propeller-blades, as hereinafter described.

The steam passing from the chamber c (or c') into the reaction-wheel through the passages c' and J (or c² and J') passes over the annular aperture c² and d in the inlet-passages, which apertures d connect with the dead-spaces G between the sides of the reaction-wheel and the side of the inclosing 35 casing, and the steam flowing into the center of wheel W thus tends to produce and maintain a vacuum in said chamber, substantially as described in my aforesaid application. The steam flowing over the passages c² likewise tends to create a vacuum in the chamber c³ exterior to the main steam-inlet passage, and these chambers c³ or c⁷ (at the opposite side of the engine) can be connected by a pipe q (or q') to the adjacent dead-space G (G') of the wheel-chamber, so that the suction created in the chamber c³ may be utilized to produce partial vacuum in the chambers G G'. Valves V V' are interposed between the chambers C³ and pipes q q', respectively, so that if the chamber is not in use as a suction-chamber it can be cut off, so the communication between the chambers c³ c⁷ and spaces G G' can be cut off at will.

In some instances I propose to utilize the 60 chambers c³ c⁷ to supply additional steam to the engine. For this purpose the chambers c³ c⁷ at opposite sides of the engine may be connected by pipes K K' to the steam-supply, and whenever it is desired to augment the power of the engine the valve V or V'

should be closed and the valve K or K' opened, according to which direction the engine is running, and then the steam will be jetted through the opening c² c⁸ into the wheel and increase the reactive power of said 70 wheel.

The propeller P may be in general appearance and construction similar to those in ordinary use; but in this instance each propeller-blade is provided with a passage p, 75 which opens out through the end of the blade, which is provided with recess p', in which is a valve p², which is so pivoted that as the propeller-blade rotates the water will cause the long arm of said valve to turn over 80 in the direction opposite to that in which the blade is moving. The space between the inner edge of this valve p² and the bottom of pocket p' forms a continuation of passage p which will incline or lead in a direction opposite to that of the rotation of the blade, so that the movement of the blade through the water creates a suction in the passage p. The passage p communicates by a lateral passage p¹ in the hub of the blade with a chamber v 85 at the end of the bearing F².

The free fitting ring w is interposed between the hub of the propeller and the end of the housing of the bearing F², so as to diminish the leakage of water between the hub and the end of the housing. As the propeller rotates, therefore, it will be obvious that the suction of the propeller-blades through the water will create a partial vacuum in the chamber v', and this chamber communicates 95 with the hollow housing M by means of passages e in the journal-bearing F², and consequently if the openings g n are closed in said housing a partial vacuum will be created therein, and if opening n be closed but water 100 admitted in said housing the water will be drawn from the housing through the openings e in the journals F² and thence through chamber v and passages p in the propeller-blades and discharged therefrom. 110

The reaction-wheels can be driven at such speed that the passages in the propeller-blades (which open automatically in the direction opposite their rotation) will move through the water at such high velocity that 115 a powerful suction will be created through the passage p and the housing, and this suction by reason of the peculiar construction of the propeller-blades and the automatic action of the valves p² will be more than sufficient to resist the pressure of the water at the depth at which the blades are immersed in the water, and this suction not only produces a partial vacuum in the housing, but will remove all steam and other leakage from the 120 housing and discharge it through the blades of the propeller.

In practice I propose to connect the housing M by suitably-valved piping with the spaces G G' and other parts of the engine 130

wherein the moving parts are subjected to skin friction, so that the propeller can be utilized as a means for removing this skin friction instead of or as auxiliary to the jets 5 d^4 and $c^2 c^8$. When the engine is stopped, water would naturally tend to pass back through the passages in the propeller-blades into the chamber v , and to prevent its passing from said chamber into the housing M , I 10 place an annular valve-disk i loosely on the shaft C within the chamber v , so that if water flows into said chamber this valve will be moved back against the end of the journal-bearing F^2 and close the passages e .

15 Operation: Steam or elastic fluid is admitted through inlet T , (or T'), into chamber c , and dilates axially in the expanding annular passage c' , (or c^5), surrounding the shaft C , acquiring a high velocity from its 20 initial pressure and expansive force combined, and rushes over the annular jet-opening c^7 , (or c^8), producing induction in chamber c^3 (or c^7) and its communicating passages and a partial vacuum in the wheel- 25 spaces G and G' when connected therewith and continuing passes over the jet-passages or running-joint d or d^4 , flows into the reaction-wheel W and issues at its peripheral jet-openings into the chamber A and passes 30 on to the condenser through the outlets A^6 .

The reaction of the jets imparts rotary motion to the wheel in the direction opposite to the flow of steam therefrom and revolves shaft C and propeller P , whose automatically-controlled passages p open in the opposite direction whichever way the blades revolve, so that the outer ends of said passages will be drawn through the water at a higher velocity than that at which water will flow 40 thereinto at the depth of their immersion, and thus produces a continuous suction and induction of the efflux of the journals and the circulating water from the shaft-casing M . The small steam leakage in this machine is 45 used to drive away the lubricant after it enters the first thrust-collars $f f'$ of the journals F and F' and discharge it into the annular chambers $h h'$, which are drained in any suitable manner through outlets $O O'$, 50 and may be returned to the journals through pipes $l l' l^2$ and is prevented from wasting by the oil-catching annular flange r and the collar r' on the shaft C . The ring w at the running-joint between the hub of the propeller P and the end of the projecting shaft-tunnel prevents too much leakage when any 55 endwise movement of the shaft occurs, as it does when reversing the motion. The valves $V V'$ are used to open or close the 60 passages connecting the wheel-casing with the jet-flange J when desired and the valve $K K'$ to admit more steam when required, and the T 's $q q'$ and the flanged opening n in the shaft-tunnel M may be connected with 65 suitable valves (not shown in the drawings)

in any convenient manner to withdraw matter from the wheel-chambers $G G'$ by the action of the propeller P .

The passages in the propeller-blades may have their outward ends flattened and provided with hinged covers to open and close automatically instead of thickening out the blades or may have apertures opening through the blades and curved in one direction on one side of the blades and curved in 70 the opposite direction on the other side, so that the same effect will be secured when revolving in either direction, and many other methods, such as channels provided with water-guiding surfaces or internal small 80 independent valves, may be employed to allow the escape from one set of passages while rotating in one direction, and the other passages may in a like manner allow the efflux when revolving in the opposite direction and still be within the explanation 85 herein shown.

The valuable features of this invention are not confined to reaction-turbines, as the casing may be elongated to admit of a drum or 90 wheels having radial vanes moving between fixed steam-reversing blades and utilize the induction of the steam for exhausting and also use a little of its entering pressure for driving away and preventing all lubricants 95 from mingling with that which is to be condensed and returned to the boilers.

Having thus described my invention, what I claim as new, and desire to secure by Letters Patent, is—

1. In combination, a turbine-engine, a propeller-shaft actuated thereby, a chambered housing for the shaft, a propeller on said shaft adapted to produce partial vacuum or suction in the housing, and means whereby said turbine can be driven forward or backward.

2. In combination, the propeller-shaft, its housing, and a propeller provided with passages connecting with the housing, whereby partial vacuum or suction is created in the housing when the propeller is rotated.

3. The combination of a propeller-shaft, its housing, a propeller on said shaft provided with passages connecting with the housing, whereby a partial vacuum is created in the housing when the propeller is rotated; with a turbine connected with the propeller-shaft, substantially as described.

4. In combination, the propeller-shaft, its housing, and a propeller provided with passages connecting with the housing, whereby partial vacuum or suction is created in the housing when the propeller is rotated; with a turbine-engine connected with propeller-shaft having oppositely-controlled jet-passages, whereby it may be driven in either direction.

5. The combination of a propeller-shaft, a propeller thereon having blades provided

with passages and adapted to create a suction when the propeller is rotated; with a turbine-engine connected with said shaft; and connections between the engine-casing and the propeller-passages whereby the propeller is caused to remove skin friction in the engine.

6. The combination of a propeller-shaft, a propeller thereon having blades provided with passages adapted to create a suction when the propeller is rotated; with a turbine-engine having opposite series of jet-passages whereby it is adapted to be driven in either direction, and connections between the propeller-shaft casing and the propeller-passages whereby the propeller is caused to partially exhaust the casing.

7. The herein-described reaction turbine-engine, comprising a casing having a closed expansion-chamber, and a reaction-wheel inclosed in said chamber provided with oppositely-disposed jet-passages, and means for admitting expansive fluid to either set of said passages whereby the wheel may be driven in either direction.

8. The herein-described reaction turbine-engine, comprising a casing having a closed annular expansion-chamber, a reaction-wheel inclosed in said chamber having its periphery fitted to the mouth of said chamber and provided on opposite sides with oppositely-disposed jet-passages, and means for admitting expansive fluid to either set of said passages whereby it may be driven in either direction.

9. The combination of a propeller-housing, a propeller provided with passages in its blades communicating with said housing, and automatic devices whereby the passages are caused to open in a direction contrary to the movement of the blades.

10. The combination of a turbine-engine, a propeller-shaft driven thereby, a housing for said shaft, a propeller mounted on said shaft provided with passages in its blades communicating with said housing, and automatic devices whereby passages are caused to open in the direction contrary to the movement of the blades.

11. The herein-described reaction turbine-engine, comprising a casing having an expansion-chamber, and a reaction-wheel provided with oppositely-disposed jet-passages, and means for admitting expansive fluid to either set of said passages whereby the wheel may be driven in either direction; in combination with a propeller-shaft driven by said engine, a housing for said shaft, a propeller attached to said shaft having passages in its blades, and a chamber communicating with the said passages and with the housing, where-

by the rotation of the propeller produces a vacuum in said chamber and housing.

12. The herein-described reaction turbine-engine, comprising a casing having an annular expansion-chamber, a reaction-wheel having its periphery fitted to the mouth of said chamber and provided on opposite sides with oppositely-disposed jet-passages, and means for admitting expansive fluid to either side of said wheel whereby it may be driven in either direction; in combination with a propeller-shaft driven by said engine, a housing for said shaft, a propeller attached to said shaft having passages in its blades, a chamber communicating with the said passages and with the housing, whereby the rotation of the propeller produces vacuum in said chamber and housing.

13. The herein-described marine engine, comprising a rotatable shaft, a propeller, a casing surrounding part of said shaft provided with an annular expansion-chamber, a reaction-wheel mounted on said shaft within said casing and communicating with said expansion-chamber, and means for admitting expansive fluid to said wheel, a housing inclosing said propeller-shaft, a propeller on the exterior end of said shaft having passages in its blades and hub, devices whereby the passages are caused to open automatically in a direction contrary to the rotation of the blade, and a communication between said passages and said housing, for the purpose and substantially as described.

14. The herein-described marine engine, comprising a rotatable shaft, a propeller, a casing surrounding part of said shaft provided with an annular expansion-chamber, a double reaction-wheel mounted on said shaft within said casing and communicating with said expansion-chamber, said wheel having oppositely-disposed series of jet-passages on its opposite faces, and means for admitting expansive fluid to opposite sides of said wheel at will, a housing inclosing said propeller-shaft, a propeller on the exterior end of said shaft having passages in its blades and hub, devices on the propeller-blades whereby the passages are caused to open automatically in the direction contrary to the rotation of the blade, and a communication between said passages and said housing, substantially as described.

In testimony that I claim the foregoing as my own I affix my signature in presence of two witnesses.

HENRY A. DUC, JR.

In presence of—

ARTHUR E. DOWELL,
L. E. WIRTHAM.
